ARTICLE OF JEWELRY AND METHOD FOR
MAKING SAME

Israel Roskin, New York, N. Y.

Application August 22, 1941, Serial No. 407,869

12 Claims. (Cl. 63—15)

This invention relates to jewelry and to a method for making the same.

One of the objects of my invention is to provide an article of jewelry, such as a ring, having novel setting means for retaining ornamental elements and more particularly ornamental elements of a fragile nature, such as pearls or thin-walled objects.

Another object of my invention is to provide an article of jewelry of the character described having no visible individual setting means for the separate ornamental elements, whereby the beauty and decorative effect of these elements is enhanced.

A further object of my invention is to provide an article of jewelry of the character described having a reflecting background which is visible around substantially the entire periphery of each of the apparently unsupported ornamental objects.

An additional object of my invention is to provide an improved method of setting a plurality of fragile ornamental elements in alignment in an article of jewelry without subjecting them to compression.

Other objects of this invention will in part be obvious and in part hereinafter pointed out.

The invention accordingly consists in the features of construction, combinations of elements, and arrangement of parts which will be exemplified in the construction hereinafter described, and of which the scope of application will be indicated in the claims.

In the accompanying drawing, in which are shown various possible embodiments of this invention,

Fig. 1 is a side view in partial section of a ring embodying my invention with a portion thereof cut away to show the pearls comprising the ornamental elements;

Fig. 2 is a side view of said ring;

Fig. 3 is an enlarged sectional view taken substantially along the line 3—3 of Fig. 1;

Fig. 4 is a view in partial section showing a step in preparing the ornamental elements for mounting in a ring;

Figs. 5, 6 and 7 are sectional views of the separate parts of the ring before assembly;

Figs. 8 and 9 are fragmentary sectional views showing successive steps in assembling the ring parts;

Fig. 10 is a fragmentary sectional view showing a step in assembling a ring embodying a modified form of my invention;

Fig. 11 is a fragmentary sectional view of a ring embodying thin-walled hollow ornamental elements;

Fig. 12 is an enlarged perspective view of one of the ornamental elements shown in Fig. 11;

Fig. 13 is a view similar to Fig. 11 of a ring employing laminar ornamental elements; and

Fig. 14 is an enlarged perspective view of one of the ornamental elements shown in Fig. 13.

In general, I accomplish the objects of my invention by providing an article of jewelry in which the ornamental objects are strung together in abutting relationship and are disposed on an elongated supporting surface provided with flanges along its longitudinal edges, at least one of which flanges is non-integral with the supporting surface and is suitably held thereto.

Referring now to the drawing, and more particularly to Figs. 1 through 3, I have there shown a ring 20 embodying my invention. Said ring comprises a plurality of small pearls 21 of a substantially uniform spherical outline. Each of the pearls is provided with a diametric aperture 22 through which is threaded a flexible string 23 whose ends are permanently joined together, as by twisting, to form a continuous unbroken loop of pearls. The string is fabricated from a material, such as stainless steel, silver or the like, which has an appreciable tensile strength and is non-corrosive.

The loop of strung pearls is disposed in an unbroken annular channeled member 24 comprising a base 25 and a pair of flanges 26 and 27. The loop of pearls and the channeled member 24 are so proportioned that the inner circumference of the loop is of the same length as the circumference of the outer surface of the channel base 25, and the space between the flanges 26 and 27 is equal to the diameter of the pearls 21. The loop is thus firmly anchored in the channeled member against translatory movement normal to the flanges 26 and 27 and base 25, although the pearls are free to rotate around the string 23 and revolve about their own axes to permit cleaning and for other purposes.

Both the flanges 26 and 27 are non-integral with the base 25, being permanently secured thereto by suitable means, such as an upset along the edges of the base, of such nature that little, if any, compressive force is applied to the pearls during or after attachment of the flanges.

In assembling the ring, I first form a strand of pearls by threading a plurality of uniform, apertured pearls 21 onto the string 23. Suf-

cient pearls are employed to form a strand having an overall length equal to or slightly less than the desired strand length for the size of ring being made. The ends of the string are then permanently joined at 29 to form a continuous loop 28 of pearls (see Fig. 4).

The pearl loop is mounted upon the base support 25 between the flanges 26 and 27 with the twist 29 pointed toward an edge of said support. The channel member 24 comprising said support and flanges may be fashioned in the following manner, to facilitate assembly:

The flat band 30 (Fig. 6) from which the base 25 is formed has both of its edges 31 beveled to acute points. Each of the annular discs 32 and 33 (Figs. 5 and 7), whose central aperture is of the same diameter as the external diameter of the band 30, is provided with a bevel 34 on one face adjacent its inner periphery, leaving a narrow band 35 adjacent its other face. The thickness of the discs 32 and 33 is governed by design considerations, and their width is preferably at least equal to the radius of the pearls 22. The width of the band 30 is equal approximately to the diameter of the pearls 22 plus the combined thickness of the discs 32 and 33. The band 30 may be plated as with cadmium or chromium to impart a silvery finish thereto, which serves as good reflecting background for the pearls.

The pearl strand is slipped over the band 30 and the annular discs 32 and 33 are also disposed on said band at opposite sides of the strand. If at this time the loop 28 is slightly too large, its circumference may be reduced by further twisting the ends of the string 23. The beveled edge of the band is then upset with any suitable tool, as for example a burnisher 36, the upset metal being forced against the bevel 34 on the discs, leaving a rounded inner edge 37 on the band.

During upsetting, the ring parts may be laid upon a support 38 with the unattached disc 33 underneath. Each edge of the ring is upset separately. If the width of the bands is slightly greater than the diameter of the pearls plus the combined thickness of the discs, as shown in Fig. 8, a layer 39 of compressible material, such as a sheet of paper, may be placed under the ring. This will permit the edge of the band not being upset to extend below the lower disc 33 substantially to the extent that the edge of the band being upset projects above the upper disc 32. The ring is then reversed and the other edge of the band upset.

It will be observed that during upsetting the force exerted by the burnisher 36 is almost wholly parallel to the plane of the discs 32 and 33, and that, as a result, very little, if any, compressive force is applied to the pearls 21 either during or after upsetting.

The ring is then lapped to remove traces of the seam between the base 25 and flanges 26 and 27, and polished to provide a high finish and remove the silvery plate from all exposed portions of the base except that underlying the pearls 21.

It will be noted that the pearls abut one another, thus concealing the string 23; and the mounting means does not surround the periphery of the individual small pearls in the fashion of present day settings for small gems and like ornamental articles. As a result of this construction, the reflecting and supporting surfaces are almost wholly spaced from the pearls, thus providing an attractive background which creates the effect of an invisible supporting means and enhances the appearance of the ring.

In Fig. 10 I have shown a ring 40 embodying a modified form of my invention in the final upsetting step. Said ring is similar to the ring 20 in construction and method of assembly, except that one of the flanges 41 is integral with the base 42 and the other flange 43 is attached to the base by upsetting.

Although in Figs. 1 through 10 I have disclosed the ornamental elements as comprising a plurality of small uniform pearls, it will be apparent that ornamental elements of various shapes and arrangement of shapes may be employed. For example, elements of different size and the same or different shapes may be employed at random or in regular series of two or more elements; or the ornamental elements may carry ornamental designs thereon to give special ornamental effects. Specific examples of rings embodying these latter forms are shown in Figs. 11 through 14.

In Figs. 11 and 12 the ornamental elements 50 comprise small U-shaped pieces having a top wall 51 with an embossed design, such as a flower 52, and a pair of integral depending side walls 53 and 54. Aligned apertures 55 are formed in the side walls 53 and 54 for receiving the string 56. Since the top wall 51 and side walls 53 and 54 are thin, this type of ornamental element needs a special support, such as is provided by my invention, which will not compress and distort said elements during mounting. The flanges and base of the ring in Fig. 11 may be constructed and assembled in the same manner as that shown in Figs. 1 through 9.

In Figs. 13 and 14 I have shown still another form of element 60. This element comprises a plate 61 which may be fashioned in any shape, as for example with two angularly diverging legs 62 and 63. An aperture 64 is substantially centrally disposed to receive a string 65. When a ring constructed in accordance with my invention and including this form of element is assembled, an unusual striated ornamental effect will be produced on the surface thereof.

It will thus be seen that there is provided a device and method for making the same in which the several objects of this invention are achieved, and which is well adapted to meet the conditions of practical use.

As various possible embodiments might be made of the above invention, and as various changes might be made in the embodiments above set forth, it is to be understood that all matter herein set forth or shown in the accompanying drawing is to be interpreted as illustrative and not in a limiting sense.

Having thus described my invention, I claim as new and desire to secure by Letters Patent:

1. A ring comprising a channel shaped annular member, said member comprising a rigid unbroken annular band and a pair of annular flanges, at least one of said flanges being non-integral with said band, means to permanently attach said non-integral flange to said band, a plurality of ornamental elements disposed in said member, said elements having apertures therein, and a flexible string threaded through the apertures, said string comprising a loop whose inner circumference is less than the outer circumference of said flanges.

2. A ring comprising a channel shaped annular member, said member comprising a rigid unbroken annular band and a pair of annular flanges of uniform thickness, at least one of said flanges being non-integral with said band, means

to permanently attach said non-integral flange to said band, a plurality of ornamental elements, each of said elements having an aperture, and a flexible string threaded through said elements, the ends of said string being permanently joined to form a continuous loop of ornamental elements, the inner circumference of said loop being less than the outer circumference of said flanges, said loop being disposed between said flanges.

3. A ring comprising a channel shaped annular member, said member comprising a rigid unbroken annular band and a pair of annular flanges of uniform thickness extending perpendicularly outwardly from opposite edges of said band, at least one of said flanges being non-integral with said band, means to permanently attach said non-integral flange to said band, a plurality of ornamental elements, each of said elements having an aperture, and a flexible string threaded through said elements, the ends of said string being permanently joined to form a continuous loop of ornamental elements, the inner circumference of said loop being substantially equal to the outer circumference of said band and less than the outer circumference of said flanges, said loop being disposed between said flanges.

4. A ring comprising a channel shaped member, said member comprising a rigid unbroken annular band of uniform thickness and a pair of annular flanges of uniform thickness extending perpendicularly outwardly from opposite edges of said band, at least one of said flanges being non-integral with said band, a plurality of ornamental elements of uniform size and shape, each of said elements having an aperture, and a flexible string threaded through said elements, the ends of said string being permanently joined to form a continuous loop of ornamental elements, the inner circumference of said loop being substantially equal to the outer circumference of said band and less than the outer circumference of said flanges, said loop being disposed between said flanges, an annular peripheral portion of said band adjacent said non-integral flange being upset to permanently attach said flange to said band and firmly but lightly press said elements between said flanges.

5. A ring comprising a channel shaped annular member, said member comprising a rigid unbroken annular band and a pair of annular flanges of uniform thickness extending perpendicularly outwardly from opposite edges of said band, at least one of said flanges being non-integral with said band, a plurality of pearls of uniform size each of which has an aperture therethrough, and a flexible string threaded through said pearls, the ends of said string being permanently joined to form a continuous loop of pearls, the inner circumference of said loop being substantially equal to the outer circumference of said band and less than the outer circumference of said flanges, said loop being disposed between said flanges, an annular peripheral portion of said band adjacent said non-integral flange being upset to permanently attach said flange to said band and firmly but lightly press said pearls between said flanges.

6. A ring comprising a channel shaped annular member, said member comprising a rigid unbroken annular band and a pair of annular flanges of uniform thickness extending perpendicularly outwardly from opposite edges of said band, at least one of said flanges being non-integral with said band, a plurality of ornamental

elements each including a top wall and a pair of integral depending side walls, said side walls having aligned apertures therein, and a flexible string passing through said apertures, the ends of said string being permanently joined to form a continuous loop of said ornamental elements, the inner circumference of said loop being equal to the outer circumference of said band and less than the outer circumference of said flanges, an annular peripheral portion of said band adjacent said non-integral flange being upset to permanently attach said flange to said band and firmly but lightly press said elements between said flanges.

10 7. A ring comprising a channel shaped annular member, said member comprising a rigid unbroken annular band and a pair of annular flanges of uniform thickness extending perpendicularly outwardly from opposite edges of said band, at least one of said flanges being non-integral with said band, a plurality of similarly shaped plates each having an aperture therethrough, and a flexible string passing through said apertures, the ends of said string being permanently joined to form a continuous loop of said plates, all of said plates being similarly arranged on said loop, the inner circumference of said loop being equal to the outer circumference of said band and less than the outer circumference of said flanges, an annular peripheral portion of said band adjacent said non-integral flange being upset to permanently attach said flange to said band and firmly but lightly press said plates between said flanges.

15 8. A ring comprising a channel shaped annular member, said member comprising a rigid annular band of uniform thickness and a pair of annular flanges of uniform thickness extending perpendicularly outwardly from opposite edges of said band, at least one of said flanges being non-integral with said band, a plurality of apertured fragile ornamental elements of uniform size, and a flexible string threaded through said elements, the ends of said string being permanently joined to form a continuous loop of ornamental elements, the inner circumference of said loop being substantially equal to the outer circumference of said band, said loop being disposed between said flanges, the outer edge of said non-integral flange lying adjacent said band being beveled, an annular portion of said band adjacent said bevel being upset to lie against said bevel whereby to permanently attach said flange to said band and firmly but lightly press said elements between said flanges.

20 9. A method of making a ring of the character described comprising threading a plurality of apertured fragile ornamental elements onto a string, permanently connecting the ends of the string, disposing the loop of ornamental elements thus formed around a rigid annular band, disposing annular flanges around said band on both sides of said loop with one surface of each of said flanges in abutment with said ornamental elements, and then permanently attaching said flanges to said band so as to lightly but firmly press said elements between said flanges.

25 10. A method of making a ring of the character described comprising threading a plurality of apertured fragile ornamental elements onto a string, permanently connecting the ends of the string, disposing the loop of ornamental elements thus formed around a rigid annular band, disposing annular flanges around said band on both sides of said loop with one surface of each of said

flanges in abutment with said ornamental elements, and then upsetting the edges of said band to attach said flanges thereto so as to lightly but firmly press said elements between said flanges.

11. A method of making a ring of the character described comprising threading a plurality of apertured fragile ornamental elements onto a string, permanently connecting the ends of the string, disposing the loop of ornamental elements thus formed around a rigid annular band having beveled edges, disposing annular flanges, one of whose surfaces adjacent the inner periphery thereof is beveled, around said band on both sides of said loop with the bevels on said flanges facing outwardly and with the inwardly facing surfaces of said flanges in abutment with said ornamental elements, and forcing the beveled edges

of said band against the bevels of said flanges so as to lightly but firmly press said elements between said flanges.

12. In a method of making a ring of the character described, those steps comprising threading a plurality of apertured fragile ornamental elements onto a string, permanently connecting the ends of the string, disposing the loop of ornamental elements thus formed around a rigid annular band, said band having one annular peripheral flange therearound, disposing an annular flange around said band and in abutment with one side of said loop of ornamental elements, and then permanently attaching said flange to said band in such manner as to lightly but firmly press said elements between said flanges.

ISRAEL ROSKIN.
